(57) **CLAIM**

The ornamental design of a television receiver, as shown in
the attached drawings and described herein.

DESCRIPTION

FIG. 1 is a front elevation view of a television receiver showing
the new design;

FIG. 2 is a rear elevation view of FIG. 1;

FIG. 3 is a right-side elevation view of FIG. 1;

FIG. 4 is a left-side elevation view of FIG. 1;

FIG. 5 is a top plan view of FIG. 1;

FIG. 6 is a bottom plan view of FIG. 1;

FIG. 7 is a front, top, and right-side perspective view of FIG.
1; and,

FIG. 8 is a rear, top, and left-side perspective view of FIG. 1.
The article relates to a thin-type television receiver.
